(Cl. D2—2)

The dominant feature of my design resides in a girdle having a front panel construction that is criss-crossed along the bottom edge thereof and a back construction in which a panel extends across the top portion and two spaced panels extend downwardly from the bottom edge of the top panel to the bottom of the girdle to form a pillar-and-lintel configuration, there being a material-contrasting rectangular insert between said spaced panels and extending downwardly from the bottom edge of said top panel to the bottom of the girdle.

I claim:

The ornamental design for a girdle, as shown and described.
